CLAIM

The ornamental design for a boat fender, as shown and described.

DESCRIPTION

FIG. 1 is a perspective view of a boat fender showing my new design.

FIG. 2 is a front side view of the boat fender of FIG. 1.

FIG. 3 is a back side view of the boat fender of FIG. 1.

FIG. 4 is a left side view of the boat fender of FIG. 1.

FIG. 5 is a right side view of the boat fender of FIG. 1.

FIG. 6 is a top view of the boat fender of FIG. 1; and,

FIG. 7 is a bottom view of the boat fender of FIG. 1.

The dash-dash broken lines illustrate unclaimed portions of the boat fender and form no part of the claimed design. The dash-dot broken lines illustrate boundaries of the claimed design and form no part of the claimed design.

1 Claim, 6 Drawing Sheets
